Assignee, Parry, Hard, Parry & Co., Inc.

Attn:

UNITED STATES PATENT OFFICE.

NORMAN REGINALD JACOBSEN, OF WELLINGTON, NEW ZEALAND.

GOLF TEE.

Application filed January 13, 1928, Serial No. 246,547, and in New Zealand February 11, 1927.

This invention provides an improved golf tee.

The object of the invention is to provide a golf tee that will overcome the difficulties experienced with existing tees, and in particular, that will enable the ball to be kept sufficiently off the ground and that will avoid having any unnecessary resistance to the head of the club if a shot is incorrectly played. Further objects are to diminish as far as possible distraction of attention caused, for example, by fear of meeting resistance, and to increase security of the tee itself.

According hereto the tee consists of a disc provided with a central shank or pin adapted to be pushed into the ground. From the upper surface of the disc project upwards preferably three flexible projections upon which the golf ball is to be placed, a lug being provided at one portion of the periphery to which may be attached a chain or cord attached to an anchor disc, weight, or the like which will lie upon the ground so that after the ball is struck the tee will not be greatly displaced, and also enables the tee to be readily lifted out of the ground.

The invention will be described with the aid of the accompanying drawings, where-
30 in:

Figure 1, is a perspective view showing the tee in use.

Figure 2, is a cross section of the tee.

Figure 3, is a plan, and

Figure 4, a sectional plan of the tee.

Figure 5, is a cross section of a modification.

Referring to the drawings, the tee consists of a disc or button of rubber 1 slightly convex upon its upper surface and having projecting upward therefrom three flexible projections 2 pointing slightly outwards upon which the golf ball 3 is placed (see Figure 1). A lug 4 having a hole is formed integral

45 with the disc to which lug may be attached a cord 5 from a metal anchor or disc 6 preferably sliding on the cord to the other end of which is attached another tee. This anchor prevents the tee becoming too far displaced after the ball has been struck, and also enables the tee to be readily lifted out

of the ground. Usually two of the tees would be used and attached to the anchor 6, one having short projections and the other having considerably longer projections, one or other of which is used according to the direction of the wind.

The disc 1 of rubber is moulded around a suitable metal disc or cap 8 (see Figure 2) from which projects the shank formed of a pin 9, a disc of fabric 10 being embedded in the rubber just beneath the disc 8.

The pin 9 is preferably attached to the disc 8 as shown in Figure 2, where the head 11 of the pin is inserted within the disc 8 which is of brass so that the rubber will vulcanize to it, and the pin is of iron so that the rubber will not adhere to it during vulcanization, and the pin at the same time will not be rigidly fixed to the cap 8.

In Figure 5, the head 11 of the pin 9 is inserted between two circular pieces of canvas 12, thus giving a greater degree of flexibility than in the former case.

What I claim is:

1. A golf tee consisting of a disc of rubber or similar flexible material, flexible projections extending upwards from the disc at or near the circumference thereof, upon which projections the golf ball is placed, and a shank projecting from the underside of the disc for insertion into the ground, discs of material embedded in said rubber disc to which the head of said shank is connected in such a manner that the joint between the shank and the discs of material is flexible, substantially as described.

2. In the golf tee as claimed in claim 1 one of the discs made of metal and receiving the head of the shank in such a manner that movement of the head is permitted within the disc of metal whereby the joint between the shank and the discs is flexible, substantially as described.

3. In the golf tee as claimed in claim 1, said flexible projections pointing in an outwardly direction, substantially as and for the purpose described.

4. A golf tee consisting of a disc of rubber or similar flexible material, flexible projections extending upwards from the disc at or near the circumference thereof upon which

projections the golf ball is placed, and a shank projecting from the underside of the disc for insertion into the ground, a metal disc embedded in said rubber disc to which said shank is connected and a disc of fabric embedded in the rubber immediately below the metal disc, substantially as described.

5. A golf tee as claimed in claim 1 a shank having a head embedded in the rubber disc and a piece of canvas above and below said head, substantially as described.

In testimony whereof, I have signed my name to this specification.

NORMAN R. JACOBSEN.
